William Keane, Mine A. S.

Letter Patent

As scheduled referred to in those Letters Patent and making part of the same.
Containing a description in the name of the said William Keane, Senior,
of his improvement in the machine for making Boxes. -

It is known that I, William Keane of the Town of Mine County of Orange
and State of New York have invented a new and useful improvement
in the machine for making Boxes, which is described as following: -
Being, and to the aforesaid claiming, part of this Specification. A
reproduction of the frame of the machine A. B. the Circular. This having the
imposition of the required form and thickness to the peripheries. These dies
are about 19 $\frac{1}{4}$ inches diameter & $\frac{1}{2}$ inch thick, made of cast steel hard.
Partly such that when the dies are set edge, side, together they form a
circular cavity into which the top is inserted, projecting the required impression
to the dies. The dies have a circular hole in their centre into which a
shaft is inserted, C. C., 2 $\frac{1}{4}$ inches long and upon the centre of which, at the top of the dies are fixed. This shaft with the dies revolve on centers, C. C. C.
fixed by means of bolts, & C. C. to a Circular plate, D. The shafts are placed
parallel with each other so that the cavities in the dies form a Circular side
directly over the center of the said plate, D, and the dies revolving cut
from the center upon which the dies form a horizontal & taking them
and cast the board on the frame as described, so as to mentioned is
placed upwards the dies, when the work is immersed in water need
not, in order to prevent the water, and dies becoming hot for which purpose
I have constructed a box, G, 7 inches in length and 5 $\frac{1}{2}$ inches diameter
cast with a bottom, this, which the said die passes the center, and 1 $\frac{1}{2}$ inches high
the 2 $\frac{1}{2}$ feet long, 10 inch diameter, being so thick that it stands
upright lengthwise standing vertically having a bearing at the bottom
and another near the top, with a party G, near the center by which

it is driven, projects into the cylindrical hollow iron casting. It about 2 inches wide and is three inches high. This spindle being hollow, before it is turned, has paper skin, its centre is turned to a $\frac{1}{2}$ in. having a slot down C. at the top to receive the key, and is connected to a box, C. which bears on the centre of the spindle and keeps the box from turning. It is also a slot on the side to bear which is bolted, to receive a thread. D. bears connected to the bottom of the spindle and supports it, being connected to the lower end of a box E. The box D. has a right & left hand end for the purpose of turning the spindle up or down as the stone is cut. The handle is on the top of this box, D. for bringing the spindle down and for the purpose of taking the finished stone out and putting in another, ready to be formed, into a stone. This box is also jointed and connected as represented at F. It has an projection in the cylindrical iron box that holds the spindle. If going up into the box about 2 or 3 inches and serves to keep the spindle true, with the box it acts very as the upper bearing. When it goes as well as it turns up and down during the operation of the machine. G. is the Casting, through which the spindle passes its vertical motion, which Casting is also connected to the box, D. The handle is represented at B. H. is the fastener on the spindle to keep it from lifting out of its slot at the bottom. I. is driven by which the spindle are driven at the rate of 80 revolutions per minute for common stones. It bears to which is attached for times for holding the stone during the operation of cutting, which fixtures are common screw drivers, with a cross head and hold permanent by a slot on the top. L is the base of the frame which supports the box before it is circled on the bush with a hole in one end and a fastened by a slot down to the center rod passing through the spindle to keep it from turning; the other end of which which moves in a perpendicular slide and also prevents the center rod from rising farther than is necessary by coming against the bottom of the spindle slot. M. is a slot of the box box in this place on the circular iron plate which is set into the cylindrical iron box for strength. It is also a slot in the box as before mentioned. When both sides of the stone, diameter having the same diameter of threads on each side, are gauged.

them together by a yoke which is fixed on the sides of the shafts in order to keep the horses in the air from pushing each other but at present I see the stock drivers think horses a day good purpose . . . .

^{of the day}
Operation. The piece of iron to be formed into a sword being first secured in the top of the other piece shown in V. by its point pushing against the bottom of the iron from the action of the weight of the iron it is by the stock drivers at the top of the machine that machine shown X is put in motion by steam, water or other power, this drives the small pulleys Y, on the platform Z, these turn the spindles with the iron C and C is horizontally, the blades at the same time having a vertical movement on the stock, giving rise at the discharge from this the piece of iron to be made into a sword thus continuing the operation till the blade is entirely cut. The operation and does not then stop properly drawing forward the iron R. the last stroke is taken out another piece of iron put in and the before described operation repeated.

What I claim is, my invention and not previously known and which I desire to secure by getting Patent consists in the construction and arrangement of the several parts of the machine as before described for making swords, particularly the mode of giving the iron a simultaneous horizontal to vertical movement in one and when whilst cutting the sword by which means the sword is cut obliquely at the same time that the iron are left cut.
